INVENTOR.

L. O. Gaspar.

BY Victor J. Evans
ATTORNEY

UNITED STATES PATENT OFFICE.

LEANDRO O. GASPAR, OF MANOR, CALIFORNIA.

CAMPER'S KIT.

Application filed March 31, 1922. Serial No. 548,495.

To all whom it may concern:

Be it known that I, LEANDRO O. GASPAR, a citizen of the United States, residing at Manor, in the county of Marin and State 5 of California, have invented new and useful Improvements in Campers' Kits, of which the following is a specification.

This invention relates to a camper's kit and has particular reference to a container 10 for a collapsible plate, the plate being readily positioned within the container so that a compact and convenient kit may be produced.

The principal object of this invention is to 15 produce a device of the character described which will occupy but a minimum amount of space, and which is simple in construction and economical to manufacture.

A further object of this invention is to 20 produce a container with a novel type of handle whereby a collapsible plate may be retained in the container without danger of being accidentally displaced therefrom.

Other objects and advantages will be apparent during the course of the following description.

In the accompanying drawings forming a part of this specification, and in which like numerals are employed to designate like 30 parts throughout the same,

Fig. 1 is a top plan view of the plate,

Fig. 2 is a similar view of the plate in its nested form,

Fig. 3 is a side elevation of Fig. 2,

Fig. 4 is a sectional view showing the means for connecting the adjoining middle plate sections,

Fig. 5 is a longitudinally vertical section through a container disclosing the collapsible plate positioned therein, the view being taken on the line 5—5 of Fig. 6,

Fig. 6 is a plan view of the container, and

Fig. 7 is a fragmentary detail of the means employed for detachably securing the end 45 sections of the plate.

In the accompanying drawings wherein for the purpose of illustration is shown a preferred embodiment of my invention, the reference character "A" designates a container equipped with a handle 9, pivoted at 50 10 adjacent the upper extremity of the container on the inside thereof. This handle is provided with a spring hook-shaped portion 11 adapted to engage the plate when it is collapsed and positioned in the container.

The plate is designated as a whole by the reference character "B" and comprises a plurality of sections including end sections 12 and 13 and middle or intermediate sections 14. Each section is provided with a depending lip 15 adapted to contact with an upturned flange 16 of the adjoining section. It will be noted that each section terminates in a disc-like extremity 17, which extremity is penetrated by a pin 18 serving as a pivotal connection for the respective sections. Notches 19 are formed in the respective outer edges of the sections and receive therein a spring clip 20 which is preferably soldered to the end section 12. This clip serves to retain the sections in a nested position when the plate is collapsed.

In order that the end section 12 may be readily connected to the section 13, when the sections are extended so as to form the unitary plate structure, I have soldered to the plate 13 a metal strip 21 provided with a depending lip 22 which is receivable in an aperture 23 formed in the end section 13.

From this construction, it will be apparent that the plate can be readily extended for use and after use can be nested and positioned within the container "A". The pivoted handle 9 will then be made to assume the dotted line position as shown to advantage in Fig. 2, with its spring hook extremity 11 straddling the disc-like extremities of the respective sections. As shown in dotted line in Fig. 5, a cover is readily placed on the top of the container so as to seal in the container culinary articles such as knives, forks or spoons.

From the foregoing description taken in connection with the accompanying drawing, it will be obvious that I have devised a compact camper's kit that will occupy but a minimum amount of space, and which is simple in construction, neat in appearance and highly serviceable.

It is to be understood that the form of my invention herewith shown and described is to be taken as a preferred example of the same, and that various changes in the shape, size and arrangement of parts may be resorted to without departing from the spirit of the invention or the scope of the subjoined claim.

Having thus described my invention, I claim:—

In a device of the character described, the

combination with a container, of a handle pivoted to said container and provided with a spring hook portion, a collapsible plate including two end sections and a plurality of connected intermediate sections, each of said sections being engaged and terminating in disc-like pivoted extremities, means for

connecting the end sections when the sections are extended, and a spring clip receivable in the notches of the sections for retaining the sections in a nested position. ¹⁰

In testimony whereof I affix my signature.

LEANDRO O. GASPAR.
